United States Patent Office.

HORACE C. WILCOX, OF WEST MERIDEN, CONNECTICUT, ASSIGNOR TO
THE WEST MERIDEN BRITANNIA COMPANY, OF SAME PLACE.

Design No. 2,540, dated January 1, 1867.

DESIGN FOR THE HANDLE OF A CASTER.

The Schedule referred to in these Letters Patent and making part of the same.

TO ALL WHOM IT MAY CONCERN:

Be it known that I, HORACE C. WILCOX, of West Meriden, county of New Haven, and State of Connecticut, have invented or produced a new and original Design for Caster Handles; and I do hereby declare that the following is a full and exact description thereof, reference being had to the photographic views, in which the same letters indicate like parts.

In the accompanying views are shown a new and original design for caster handles. A is a triangular-shaped handle; *a a a* are triangular-shaped sides of a handle; *c* is a caster spindle, embellished with a bead, *d*, and fillets, *i i*, the whole combined substantially in the manner shown and described, to produce a plain rich design for caster handles.

What I claim, and desire to secure by Letters Patent, is—

A design for caster handles, substantially as herein described and illustrated.

HORACE C. WILCOX. [L. S.]
